RECEPTACLE FOR MARKING PENS

James H. Lee and James R. Pauls, Walnut Creek, Calif.,
assignors to Dymo Industries, Inc., Emeryville, Calif.

Original design application May 7, 1968, Ser. No. 11,816,
now Patent No. 217,838, dated June 16, 1970. Divided
and this application Mar. 25, 1970, Ser. No. 22,043

Term of patent 14 years

Int. Cl. D19—02

U.S. Cl. D74—5

FIG. 1 is an elevational view of a receptacle for marking pens showing our new design;

FIG. 2 is a bottom plan view thereof;

FIG. 3 is a top plan view thereof showing two apertures therein for receiving two round marking pens; and

FIG. 4 is a top plan view of another embodiment of the receptacle shown in FIG. 1 having a single aperture therein for receiving a rectangular marking pen.

This application is a division of our application Ser. No. D. 11,816, filed May 7, 1968, and now Pat. D. 217,838, granted June 16, 1970.

We claim:

The ornamental design for a receptacle for marking pens, as shown and described.
